Walter Wilford Morgenweck, Fanwood, N. J.

Application December 18, 1952, Serial No. 22,757

Term of patent 3½ years

(Cl. D34—13)

To all whom it may concern:

Be it known that I, Walter Wilford Morgenweck, a citizen of the United States, and a resident of Fanwood, county of Union, State of New Jersey, has invented a new, original, and ornamental Design for a Combined Playing Card and Poker Chip Case or Similar Article, of which the following is a specification, reference being had to the accompanying drawing, forming part thereof.

In the drawing:

Figure 1 is a perspective view of a combined playing card and poker chip case or similar article, showing my new design, the case being shown open with parts in partially withdrawn position; and

Figure 2 is a perspective view of the case, shown closed.

What is claimed is:

The ornamental design for a combined playing card and poker chip case or similar article, substantially as shown.

WALTER WILFORD MORGENWECK.
